ATTORNEYS.

UNITED STATES PATENT OFFICE.

LEWIS EDWARD YOUNIE, OF LA FAYETTE, CALIFORNIA.

DIGGING IMPLEMENT.

Application filed December 18, 1926. Serial No. 155,603.

Ordinarily digging implements, such as trenching machines, power shovel dippers, and similar devices have teeth secured to the digging edges of these implements, the cutting edges of the teeth usually projecting in front of the digging edge of the digging receptacle. I have found that the action of such teeth may be improved by placing the teeth to the rear of the digging edge, this 5 improving the digging action and simplifying the attachment of the teeth to the receptacle. Features and details of the invention will appear from the specification and claims.

The invention is illustrated in the accompanying drawings as follows:—

Fig. 1 shows a perspective view of a trenching machine bucket with teeth according to the invention in place thereon.

Fig. 2 a side elevation, partly in section, 20 of a digging edge with a tooth in place thereon.

1 marks the digging receptacle which as shown is connected with the carrying chains 2 of a trenching machine and 2^a a boom along 25 which the digging implements are carried as commonly. The digging receptacle 1 has a digging edge, or lip 3.

A number of tooth carriers 4 are secured to the digging edge. Each carrier has a hook 30 end 5 hooking over the front edge of the receptacle and is secured in place by rivets, or bolts 6. The rear end of the carrier is provided with a downturned extension 7 which is provided with a perforation 8. A tooth 9 35 has a shank 10 extending through the perforation and a cotter pin 11 extends through the rear end of the tooth locking it in the perforation. The tooth so mounted reduces the metal necessary for the tooth to a minimum, provides a means by which the teeth 40 may be readily exchanged and the teeth sharpened but the functional operation of the teeth positioned as in this invention improves the operation of the digging implement tending to hold the receptacle to its work without undesirably tilting the recep-

tacle so that it may be used in very hard and difficult material with success.

What I claim as new is:—

1. In a digging implement, the combination of a receptacle having a digging edge; tooth carriers on the underside of the receptacle; and a tooth at the rear of the edge secured to the carrier, said tooth being downwardly and forwardly inclined. 55

2. In a digging implement, the combination of a receptacle having a digging edge; tooth carriers on the underside of the receptacle and having down-turned extensions at their rear ends; and teeth having shanks secured in the extensions. 60

3. In a digging implement, the combination of a receptacle having a digging edge; tooth carriers on the underside of the receptacle and having down-turned perforated extensions at their rear ends; and teeth having shanks extending into the perforations. 65

4. In a digging implement, the combination of a receptacle having a digging edge; tooth carriers on the underside of the receptacle and having down-turned perforated extensions at their rear ends; teeth having shanks extending into the perforations; and means at the rear of the extensions locking the shanks in the perforations. 70

5. In a digging implement, the combination of a receptacle having a digging edge; tooth carriers on the underside of the receptacle, said carriers having a hook hooking over the edge; and teeth at the rear of the edge secured to the carriers. 75

6. In a digging implement, the combination of a receptacle having a digging edge; tooth carriers on the underside of the receptacle, said carriers having hooks engaging the edge and having down-turned extensions at their rear ends; and downwardly inclined teeth secured to the extensions. 85

In testimony whereof I have hereunto set my hand.

LEWIS EDWARD YOUNIE.
